UNITED STATES PATENT OFFICE.

WILLIAM R. MACKLIND, OF CLEVELAND, OHIO, ASSIGNOR TO GEORGE A. MARTIN, TRUSTEE, OF CLEVELAND, OHIO, FOR THE USE AND BENEFIT OF SAID MACKLIND AND THE SHERWIN-WILLIAMS COMPANY, OF CLEVELAND, OHIO, A CORPORATION OF OHIO.

VAPOR-REMOVING APPARATUS FOR DRYING MECHANISM.

1,192,084.

Specification of Letters Patent.

Patented July 25, 1916.

Original application filed August 10, 1912, Serial No. 714,323. Divided and this application filed August 4, 1915. Serial No. 43,594.

To all whom it may concern:

Be it known that I, WILLIAM R. MACKLIND, a citizen of the United States, and a resident of Cleveland, county of Cuyahoga, 5 and State of Ohio, have invented a new and useful Improvement in Vapor-Removing Apparatus for Drying Mechanism, of which the following is a specification, the principle of the invention being herein explained and the best mode in which I have contemplated applying that principle, so as to distinguish it from other inventions.

The present improved vapor removing apparatus is designed more especially for use 15 in connection with a continuous drying machine of the kind illustrated in my co-pending application filed August 10, 1912, Serial No. 714,323, out of which the present case has been required to be divided, such 20 drying machine being characterized, among other things, by the use of an annular drying table. It will be understood, however, that my improved vapor removing apparatus, while thus designed for use in conjunction with a drying machine of this type, 25 may also be advantageously employed in connection with other kinds of drying machines, and for that matter, may be used in removing vapors from machines which 30 treat materials in other ways than by drying the same.

The aforesaid drying machine is designed primarily for handling wet, sludgy materials which are known in commerce as pulps, 35 both in mineral and vegetable products. For example, such pulp, as is well known, is produced in the manufacture of white lead and lead oxid, zinc oxid and other pigments. All these materials, when in the 40 pulp state, are more or less refractory, both in being subjected to drying means and in letting loose of a certain percentage of the water which they carry. Owing to the large per cent. of water found in materials 45 of this class, the drying operation is complicated, and the work of attendants apt to be greatly hampered by the large volume of vapor given off.

The object of the present improvements 50 accordingly, is to provide means for the con-

tinuous collection and withdrawal of the vapors arising from the drying operation, proper, so as not only to render it convenient and healthful to work about the machine, but also to accelerate such operation. 55

To the accomplishment of the foregoing and related ends, said invention, then, consists of the means hereinafter fully described, and particularly pointed out in the claims. 60

The annexed drawings and the following description set forth in detail certain mechanism embodying the invention, such disclosed means constituting, however, but one of various mechanical forms in which the 65 principle of the invention may be used.

In said annexed drawings:—Figure 1 is a plan view of a drying machine embodying my present improved vapor removing apparatus; Fig. 2 is a radial, vertical section of such apparatus taken on the plane indicated by the line 2—2, Fig. 1; and Fig. 3 is another transverse section of a detail taken on the plane indicated by the line 3—3, Fig. 1. 75

The general features of construction characterizing the illustrative form of my improved machine, shown in the foregoing drawings, comprise in addition to the annular, and substantially horizontally disposed 80 drying table A, to which reference has already been made, various other mechanisms supported in coöperative relation to said table, including a feeding apparatus B, for depositing onto the table a layer or film of 85 the material to be dried; an apparatus C, for removing from the table the dried material, and discharging the same from the machine; and an apparatus for removing the vapor or moisture arising from the depositing of such material. The last named apparatus alone, will be described in detail in this connection, it being sufficient to note that the material feeding and removing apparatuses, together with such vapor removing apparatus, are all supported from a rotatable frame which carries such parts in proper coöperative relation to the table, and also supports the necessary operating mechanism therefor. Such frame, in the form 90 95 100

illustrated, includes a series of radial arms 16, and cross-members 17 and 18, and is centrally supported upon a column 11, as well as peripherally by means of rollers 20 upon 5 a circular track 19.

The drying table A, as already indicated, is of annular form, and is supported by means of a series of suitable supporting stands 1, upon the foundation 2, (Fig. 2).
10 The table proper, is built up of a plurality of contiguous sections that are supported upon said stands by means of inner and outer channel rings 3. The sections are in the form of sectors 4, and are hollow, the 15 upper and lower walls being connected together by webs 5, as shown in the figures just named. Pipes 6 and 7 for supplying steam and removing the water of condensation, respectively, are provided in connection with each sector, the last named pipes being connected to the inner ends of the sectors, and the bottom walls of the latter sloping toward such inner ends so as to cause the 20 condensed water to drain naturally away.

It will be understood that the drying table A, of the machine has a considerable superficial area, and there will be produced in 25 drying materials, such as those in mind, such a considerable volume of vapor or steam as to be objectionable, especially under certain weather conditions and in buildings more or less inclosed. I accordingly provide means for withdrawing and removing 30 from the apparatus substantially all such vapor, said means comprising a series of vapor collectors discharging into a central drum made up of a stationary section 34, and the rotatable section 41. The collectors themselves are in the form of hoods 35 disposed between successive radial arms 16 of said frame and are all similar with the exception of one of special construction that is mounted next to the feeding apparatus B. Each of said similar collectors is made up 40 of two side members 110 and a central key-member 111 supported from the radial arms 16 by means of rods 112, (Fig. 2), as need not be explained in detail, the lower edges 45 lying close to the upper surface of the drying table.

The specially constructed collector 113 adjacent to the feeding apparatus, as shown in transverse section in Fig. 3, differs from the other duplicate sections only in the matter of size, consisting of a single member 55 which is furthermore provided at its forward edge with an extension that projects under the feeding apparatus and substantially even with the line on which the material is deposited from such apparatus, so that the vapor produced by the material 60 dropping onto the drying table is immediately caught by the collector. This is highly important for the reason that obviously the 65 greater bulk of the vapor driven off during

the drying operation is driven off at this stage, less and less evaporation occurring as the drying progresses.

Leading from this special collector 113 adjacent to the feeding apparatus and from the central member 111 of each of the duplicate collectors, is a radial vapor-pipe 114, that is connected with the rotatable section 41 of the central vapor drum. A water-sealed joint 115 forms a tight closure between this section and the upper stationary section 34 of said drum, with which latter section is connected the main discharge vapor pipe 116. Said pipe 116 may lead to any suitable point without the building or 70 structure in which the drying machine is housed. A suitable draft should be induced in this vapor discharge pipe either by means of a fan 117, or the like located at its outer end, as shown in Fig. 2, or by connecting 75 such outer end with a stack, all as will be readily understood.

Inasmuch as the vapor will naturally tend to condense more or less, incidentally to its collection by the pipes 113 and the 80 drum into which they discharge, such pipes are arranged to incline downwardly toward the drum, and the latter is provided in its bottom with drain pipes 118 that lead to an annular trough 119 supported upon the central column 11 by means of the centering sleeve 12. This trough is, in turn, provided with a drain pipe 120 that leads to a 85 central pocket in the column and has an exterior discharge (not shown).

It will be observed that the radial vapor pipes 114, beginning with the one that follows the first pipe connected with the special collector hood 113, are of successively smaller size in cross-section, as indicated in 90 Fig. 1. Moreover, for the size of the hood 113, said first radial vapor pipe 114, is relatively the largest of the lot. The object in the foregoing proportioning of the size of these pipes is to apply the greater suction 95 to those hoods where the greater amount of vapor will naturally be expected to arise from the material that is being dried on the annular table. Otherwise a much greater suction would have to be maintained on the 100 discharge vapor pipe 116, much of such suction being wasted in the case of the hoods that pass over the material just before it is reached by the removing apparatus C.

The general operation of the machine has 105 already been sufficiently indicated, it is believed, to render clear the functioning of my improved vapor removing apparatus. The latter, together with the material feeding and removing apparatuses are carried by 110 the rotatable frame which supports them, in the direction indicated by the arrow in Fig. 1, so that, as fast as the dried material 115 on the table is taken up and removed by mechanism C, a fresh layer of wet material, 120

or sludge, is deposited by the feeding mechanism B. The table, in other words, is continually covered by a layer of material, save for the sector-portion thereof that at any 5 particular moment happens to lie between the mechanism C and D, and practically the entire remainder of the table is covered over by the series of vapor collecting hoods, which, with the corresponding series of radial vapor pipes 114, are adapted to draw off the vapors arising from the material on such portion of the table as fast as they arise, conduct them to the central vapor drum, and thence without the building, or 10 to a point of discharge where they can cause no inconvenience to the workmen, or hinder the operation of the machine. At the same time it will be obvious that the effect of such vapor collecting apparatus 15 will be to facilitate the drying operation by assisting the material in giving off the water absorbed therein, or intermixed therewith.

Other modes of applying the principle of my invention may be employed instead of 20 the one explained, change being made as regards the mechanism herein disclosed, provided the means stated by any of the following claims or the equivalent of such stated means be employed.

30 I therefore particularly point out and distinctly claim as my invention:—

1. The combination with an annular drying table, of vapor-collecting means circularly movable about said table with the center of the latter as an axis.

2. The combination with an annular drying table, of vapor-collecting means circularly movable about said table with the center of the latter as an axis, and a centrally located vapor drum connected with said vapor-collecting means.

35 3. The combination with an annular drying table, of vapor-collecting means circularly movable about said table with the center of the latter as an axis, a centrally located vapor drum, and a series of radial pipes connecting said vapor-collecting means with said drum.

4. The combination with an annular drying table, of a series of vapor-collecting hoods disposed thereover and movable in a circular direction with the center of said table as an axis, a centrally located vapor drum, connected with draft means, and a 50 series of radial pipes connecting said hoods, respectively, with said drum, said pipes being graduated in size to vary the draft effect in different hoods.

5. The combination with an annular drying table, of material-feeding means movable in a circular path over said table, a series of vapor-collecting hoods disposed over said table and similarly movable in unison with said feeding means, a centrally located vapor drum connected with draft

means, and a series of radial pipes connecting said hoods, respectively, with said drum, said pipes being graduated in size to reduce the draft effect in the hoods based on their distance from said feeding means, in a direction opposite to that of the movement of said means.

6. In drying mechanism, the combination of an annular drying table; a column centrally disposed with respect to said table; a frame rotatably supported upon said column and comprising radial arms extending over said table; vapor-collecting hoods carried between said arms in operative relation to said table; and a drum located over said column and comprising a stationary section having an exterior discharge and a movable section carried by said frame and connected with said vapor-collecting hoods.

7. In drying mechanism, the combination of an annular drying table; a column centrally disposed with respect to said table; a frame rotatably supported upon said column and comprising radial arms extending over said table; vapor-collecting hoods carried between said arms in operative relation to said table; a drum located over said column and comprising a stationary section having an exterior discharge and a movable section carried by said frame and connected with 90 said vapor-collecting hoods; and drain connections from said drum passing downwardly through said column.

8. In drying mechanism, the combination of an annular drying table; a column centrally disposed with respect to said table; a frame rotatably supported upon said column and comprising radial arms extending over said table; and a vapor-collecting hood carried between two of said arms in operative relation to said table, said hood comprising two end sections suspended from said arms and an intermediate key-section.

9. In drying mechanism, the combination of an annular drying table; a column centrally disposed with respect to said table; a frame rotatably supported upon said column and extending over said table; material feeding and drying means and vapor-collecting means carried by said frame in operative relation to said table and in circumferentially spaced relation to each other; a drum located over said column and comprising a stationary section having an exterior discharge and a movable section carried by said frame and connected with said vapor-collecting means; a hopper in said column having an opening encircling the same; and conveying means also carried by said frame, said conveying means leading 115 from said removing means and discharging into said hopper opening.

10. In drying mechanism, the combination of an annular drying table; a column centrally disposed with respect to said table; a

frame rotatably supported upon said column and extending over said table; material feeding and drying means and vapor-collecting means carried by said frame in operative relation to said table and in circumferentially spaced relation to each other; a drum located over said column and comprising a stationary section having an exterior discharge and a section carried 10 by said frame and connected with said vapor-collecting means; connections for supplying the material to be dried to said feeding means including a pipe extending from above downwardly through the relatively

stationary section of said drum and thence 15 radially outward to said means; a hopper in said column having an opening encircling the same; and conveying means also carried by said frame, said conveying means leading from said removing means and discharging 20 into said hopper opening.

Signed by me, this 2nd day of August, 1915.

WILLIAM R. MACKLIND.
